UNITED STATES PATENT OFFICE.

HENRY G. ORTH, OF FULTON, NEW YORK.

CRATE.

1,417,555.

Specification of Letters Patent.

Patented May 30, 1922.

Application filed July 3, 1920. Serial No. 393,912.

To all whom it may concern:

Be it known that I, HENRY G. ORTH, a citizen of the United States of America, and resident of Fulton, county of Oswego, State 5 of New York, have invented certain new and useful Improvements in and Relating to Crates, of which the following is a specification.

This invention relates to certain improvements in crates; and the objects and nature 10 of the invention will be readily understood by those skilled in the art in the light of the following explanations of the accompanying drawings illustrating what I now believe to 15 be the preferred embodiment or mechanical expression of my invention from among other forms, constructions and arrangements within the spirit and scope thereof.

An object of the invention is to provide a 20 crate for packing and shipping purposes that will be exceedingly light in weight, and economical in manufacture, and that can be knocked down when empty and folded into an exceedingly small space and can be 25 readily set up for use, and that embodies means for retaining the bottom and top walls in place without the use of nails and like fastening devices.

A further object of the invention is to 30 provide a knock down crate composed of so-called fiber board or other paper material, that is peculiarly adapted for packing and transporting vegetables and fruits, and that embodies improved features of construction 35 and formation, whereby the crate is rendered highly advantageous from the standpoint of the user.

With these and other objects in view my 40 invention consists in certain novel features in construction and in combinations and arrangements as more fully and particularly set forth and specified hereinafter.

Referring to the accompanying drawings:—

Fig. 1 is a perspective view of a crate embodying my invention and shown in set up 45 condition with the bottom and top applied and confined to place by the swingable bails.

Fig. 2 is a perspective view showing the 50 crate set up with the bottom in place and secured, the top being removed and the top bails in inoperative position at the crate ends.

Fig. 3, is a perspective view showing the 55 crate in collapsed or knocked down condition.

Fig. 4 is a section on the line 4—4, Fig. 1. Fig. 5 is a cross section of the crate of Fig. 6.

Fig. 6 is a perspective of a crate of modified construction.

In the embodiments illustrated, the crate consists of upright or surrounding side and end walls constituting the crate shell or body 1; a bottom 2; a top 3; and certain swingable bottom bails 4, and (usually corresponding) top bails 5.

The crate shell or body 1 is endless, and is composed of one or more sheets or panels of paper material of the required thickness 70 and strength to meet the conditions of use in the field and during transportation. I usually employ so-called fiber or pulp board of the thickness or made up of one or more plies to give the necessary strength. This 75 paper material is preferably treated to render the same waterproof. This can be accomplished by chemicals, paraffine, or by any other suitable method as will be understood by those skilled in the art.

This crate shell or body is creased or scored to permit bending at the corners, and the corner portions of said shell are preferably reinforced by fabric pasted or otherwise secured thereto.

As before stated, the paper material is scored or otherwise formed to readily bend at the lines 1^a where the side and end forming portions meet to form the corners of the set-up crate shell, so that the shell can be 90 collapsed or folded down to flat form and as readily unfolded or expanded to set up position. The shell knocks down or folds to elongated flat form with one side and end wall portions approximately resting on and 95 parallel with the other side and end wall portions.

In the embodiment illustrated by Fig. 1, the bottom 2 and top 3 are similar and interchangeable, and each is composed of a flat 100 waterproofed sheet of heavy comparatively stiff strong paper material, such as fiber board or the like. Each such sheet is notched at the corners, see 2^a or 3^a, to provide edge flanges 2^b, or 3^b joined to the rectangular 105 body of the sheet along bending lines 2^c or 3^c on which the flanges can be bent up to slip into the crate shell or body, as shown.

The rectangular body of each sheet is of approximately the same length and width 110 as the interior of the crate shell so as to close the same with the flanges of the body snugly

fitting the inner faces of the shell side and end walls. The top and bottom sheets can be supplied to the user packed in bundles with their corners notched and their flanges 5 bent down or flattened out. When the crate parts are assembled, the edge flanges can be easily bent up to proper position to permit insertion of the closure (top and bottom) in the crate shells.

10 The crate shell is provided with means such as swingable bails 4, 5, to pass over the exteriors of the closures (top and bottom) and hold them in place against the contents of the crate and from outward movement 15 from the crate shell, and also to serve the purpose of exterior straps reinforcing and bracing the entire crate structure.

In the example illustrated, each bail consists of an elongated flat strip or ribbon of 20 (preferably) waterproofed thick or heavy strong paper material, such as fiber board or the like, usually suitably reinforced by fabric or other suitable means at the corners. The paper material is preferably scored or 25 otherwise formed to provide bending lines at the corners 4^a or 5^a, so that the bails can bend without breaking when the crate shell is collapsed and set up. The ends of each bail are pivotally secured to the side walls 30 of the crate shell, at alined points (when the crate is set up) by any suitable means, although in the example illustrated, I show metal eyelets 6 for this purpose. However, I do not wish to so limit all features of my 35 invention.

Each bail is formed with a flat body of substantial width and of slightly greater length than the width of the crate and its 40 closures (top and bottom) to extend across and bear against the outer side face of a closure, with two similar flat laterally extending ends usually of the same width as the body and extending onto the outer faces of the crate shell side walls and securely and 45 permanently coupled thereto so as to withstand the strains and stresses to which said bails will be subjected when the loaded crates are handled.

The two bails for the crate bottom are arranged adjacent to the opposite ends of the 50 crate shell, and each is pivoted approximately near a lower corner of the crate and its lateral ends are of such length that the bail can swing to and can rest in inoperative 55 position embracing the adjacent crate shell end and approximately parallel with the crate shell, or can swing around to operative position transversely of the crate and passing across the bottom closure at the exterior thereof.

60 This operation is true of all the bails.

The two similar bails for the crate top closure are also arranged near the crate ends and are pivoted thereto near the upper corners of the crate shell. These bails are so

formed and arranged (although it is difficult to so illustrate the same by drawings) as to provide the clearance necessary to permit the bails to swing to operative position at the exterior surfaces of the bottom and 70 top closures.

These various bails, when permanently attached to the shell, are applied thereto at the factory and swung to positions embracing the shell ends. The crate shell with the attached bails can then be collapsed to knocked down condition, and the bails will collapse with the shell bending at the bending lines described to positions approximately parallel with adjacent portions of the shell, as shown. 75

When the shell is expanded to set up position, the bails will be thereby restored to their arched or U shape form embracing the ends of the shell. 80

When the crate is to receive its contents, 85 in the field or elsewhere, the bottom closure is inserted in the open bottom of the shell and the two lower strap bails are swung down to operative position extending around under said bottom.

When the crate is filled and ready for closing, the top closure is inserted through the open top of the shell and onto the load within the crate, and then the two upper strap bails are swung upwardly from the 95 crate ends to upright vertical position extending over and across said top.

The crate shell, top and bottom closures, and the strap bails are sufficiently flexible to permit more or less bulging or bending 100 to somewhat conform to the load and so that the bails will bend to conform to the bulging of the top and bottom closures, and maintain their closure securing operative positions against accidental displacement. However, 105 I do not wish to so limit all features of my invention.

The crate shell, and usually the top and bottom closures, are provided with suitable 110 ventilating slots or openings 10, formed therein by cuts or slots.

In the example shown, these slots 10 have enlarged end portions 10^a for the entrance of the fingers of operators in handling the loaded crates, thereby affording finger holds 115 performing the functions of handles.

If so desired, the top and bottom closures can be formed to fit the exterior of the crate shell instead of slipping down within the same. 120

Such exterior end closures 30 are similar and formed with flanges 31 permanently secured at the corners by fabric, metal or other suitable corner reinforcing and securing means 32, preferably so that the closure 125 flanges are slightly inclined or flaring. These closures with fixed flanges can be nested when packed into bundles for shipment.

The flanges of these closures are ar- 130

ranged at the exterior of the crate shell when the closures are in place on the shell, and these flanges are somewhat flexible to bend, if need be, to permit passage of bails when the strap bails are swung to operative positions across the exteriors of the closures, as hereinbefore described. The bails will usually draw the closures into shape conforming to the crate shell and the bails and to 10 permit bulging to conform to the load.

I do not wish to limit all features of my invention to the bails formed of the strips of paper material, nor to bails permanently hinged or pivoted to the shell, and it is evident that various changes, modifications, and 15 variations might be resorted to without departing from the spirit and scope of my invention as defined by the claims.

What I claim is:—

- 20 1. A crate comprising a shell or body open at the top and bottom and creased to collapse with side and end wall portions lying approximately on and parallel with the opposing side and end wall portions, top and bottom closures for said shell, and bails attached to and adapted to collapse with the body and to extend across the outer surfaces of said closures and confine the closures to the shell and brace and complete the crate.
- 25 2. A crate comprising a collapsible flexible shell, swingable top and bottom securing bails each at its ends attached to the shell, said bails formed flexible to collapse with

the shell, a bottom for said shell, and a top for said shell.

3. A crate composed of a collapsible shell, a bottom therefor, a top therefor, bottom securing arched bails at their ends pivotally fastened to the shell, and top-securing arched bails at their ends pivotally fastened to the 40 shell, said top and bottom securing bails in operative position extending across the top and bottom, respectively, to confine the closures to the shell and complete and brace the crate, and when removed to inoperative position permitting removal of the top and bottom, respectively, and collapse of said shell.

4. A crate composed of a collapsible shell, a bottom therefor composed of a sheet having edge flanges adapted to be bent up to 50 slip within the shell, a similar top for said shell, and bails to confine said top and said bottom in the shell, said bails in operative position extending across and confining the top and bottom, respectively, within the 55 shell to complete the crate, and said shell maintained in crate forming position against collapse by said bails, the top and the bottom, respectively.

5. A crate comprising a collapsible shell, 60 swingable flexible top and bottom confining bails permanently pivoted to and collapsible with the shell, and a separate top and a separate bottom for said shell.

HENRY G. ORTH.
